& Carpenter, Attys.

UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

AMMONIA, TAR, AND BENZOL RECOVERY PROCESS.

1,307,534.

Specification of Letters Patent. Patented June 24, 1919.

Application filed August 12, 1918. Serial No. 249,379.

To all whom it may concern:

Be it known that I, JOSEPH BECKER, a subject of Germany, who have declared my intention of becoming a citizen of the United States and residing in Pittsburgh, in the county of Allegheny and State of Pennsylvania, have invented a new and useful Improvement in Ammonia, Tar, and Benzol Recovery Processes, of which the following is a specification.

My invention relates primarily to the recovery of tar and ammonia, and of benzol, and its homologues, from coke-oven gas, and has for an object a simplified and efficient extraction of the tar, and also a recovery of the ammonia by a method that simplifies apparatus and economizes the heat required in the ammonia recovery; and has for a further object the recovery, directly from the gas, of a portion of benzol, and its homologues, that is carried off dissolved in the tar in the usual methods of tar-extraction from the gas, and the invention may also be applicable to the treatment of gas that is otherwise derived from the carbonization of coal, and may also have such other objects and results as are found to obtain in the processes hereinafter set forth and claimed.

In the accompanying drawings, Figure 1 is a conventional diagram illustrating an embodiment of the invention in a preferred arrangement of apparatus for practising its processes; and Fig. 2 is a key to the symbols employed in the various lines that show the connections between the apparatus indicated in Fig. 1.

5 indicates the coke-ovens from which the coke-oven gas is derived. The gas flows first into an electrical precipitator 6, which it enters at a temperature of about 80° C. At such temperature the tar is carried in the gas in the form of a finely comminuted mist, and such mist is effectively precipitated in the electrical precipitator, from which the precipitated liquefied tar is drained off into the tar-tank 7. The water and ammonia are carried through the precipitator in the form of vapor; as the gas leaves such precipitator at a temperature that is still above the water saturation point of such gas. The gas is then conducted to and enters the hot acid-washer tower 8, in which the ammonia is absorbed by the acid-solution that is kept hot

by the absorption reaction. The gas both enters and leaves the acid-washer with a 55 temperature that is still somewhat above its water saturation point, but so little above that practically no water is taken up by the gas from the acid-solution and consequently there is no precipitation of ammonium sulfate in the acid-washer tower and the gas leaves it still carrying as vapor substantially the original water content with which such gas left the ovens. The acid-solution from the said acid-washer tower 8 flows 65 into a saturator 9, carrying with it into the saturator any slight amount of ammonium sulfate that may have been precipitated. The acid-solution drained from the saturator's drain table 10 and centrifugal drier 70 11, into the mother-liquor tank 12, is forced back, by the acid pump 13, to the top of the acid-washer tower 8, a proportion of fresh acid being there continuously added from the acid-tank 14. A portion of the acid-solution from the mother-liquor tank 12 may also flow back into the saturation-bath in the saturator 9. From the acid-washer tower the gas flows into and through the cooler 15 that is sprayed with fresh water 80 from the water tank 16. The drain from this cooler flows to the naphthalene recovery apparatus. The gas issues from the cooler 15 at a temperature of about 30° C., substantially dehydrated, and having been previously freed of its tar and ammonia. Such gas passes next through the exhauster 17 and thence is forwarded in part directly to the saturator, through the gas-line 18, and in part through the by-pass 19 into the gas-line that leads from the saturator to the final cooler 20. The gas passing from the exhauster into the saturator has a temperature of about 35° C., and discharging through the saturation-bath it effects the 95 evaporation requisite to precipitate the ammonium sulfate from the bath. The gas issuing from the saturator, at a temperature of about 45° C., passes, as just above mentioned, to the final cooler 20, together with the gas coming directly through the aforesaid by-pass 19 from the exhauster. This final cooler 20 is constantly sprayed with fresh water from the before-mentioned water-tank 16, and the drain from said 100 cooler is carried to the naphthalene recovery

apparatus through the naphthalene drain line 21. The gas issues from the final cooler 20 cooled to about 20° C., still carrying substantially its entire original content of benzol and its homologues, and then passes into the benzol scrubber 22, in which the benzol and its homologues are extracted by a constant flow of straw oil entering the scrubber through the oil line 23. The benzolized oil 5 drains from the scrubber 22 into the benzolized oil line 24 leading to the further apparatus for the recovery of such benzol and its homologues. The gas from the benzol scrubber passes to the gas-holder 25 and thence 10 to its final distribution, in part back to the ovens to be used as the fuel-gas for their firing, and in part to whatever other service such clean coke-oven gas may be employed for.

20 The taking out of all of the tar while the gas is still hot, and by a precipitation method that does not require the gas to pass through absorption films or sprays of tar, saves the absorption of benzol, and its 15 homologues, that occurs when the gas is either cooled to effect tar extraction or passed through films or sprays of liquefied tar, and there is thus a substantial increase in the final recovery of benzol and its homologues directly from the gas.

The tar recovery is complete and is substantially free of admixture of other condensate. And the ammonia is effectively and completely taken out in the acid - washer, 25 and the ammonium sulfate is precipitated in the saturator with gas that has not undergone any reheating operation other than the heating incidentally derived from the adiabatic compression to which it is subjected in 30 passing through the exhauster. The naphthalene is taken off with the drainage from the first cooling operation to which the gas is subjected, but this cooling operation is subsequent to both the tar precipitation and 35 the ammonia absorption, both of which are effected while the gas is still at high temperature; and so naphthalene stoppages in the apparatus are effectively avoided.

The processes of the invention may be 50 practised in various ways, other than the particular embodiment that has been described for purposes of illustration, and still be within the scope and subject matter of the claims hereinafter made.

55 In my co-pending application Serial No. 249,378, filed of even date with the present application, I have set forth and directed claims to the general process of absorbing the ammonia from the hot gas passing 60 through an acid-wash and then leading the hot ammonia-charged acid-solution into a saturation bath through which the ammonia-free and relatively low-temperature gas is passed and carries off the evaporation 65 from such bath.

I claim:

1. In a process for the recovery of tar and ammonia from coke-oven gas, the combination of steps that consists in: extracting the tar from the coke-oven gas hot; passing 70 such hot gas through an acid-wash to absorb the ammonia of the gas; discharging the mother-liquid from such acid-wash into a saturation-bath; passing the tar-free and ammonia-free gas through a cooling and dehydrating operation; and passing such gas through said saturation-bath, to effect deposition of the ammonium sulfate; substantially as specified.

2. In a process for the recovery of benzol 80 and its homologues from coke-oven gas, the combination of steps that consists in: electrically precipitating the tar residue from the gas while the latter is still hot enough to preclude appreciable absorption of benzol by 85 the tar precipitated; and then passing the gas through ammonia recovery and benzol extraction operations; substantially as specified.

3. In a process for the recovery of tar, 90 ammonia and benzol, and its homologues, from coke-oven gas, the combination of steps that consists in: electrically precipitating the tar residue from the gas while the gas is enough superheated substantially to preclude the tar from absorbing the benzol, and its homologues, in the gas; passing the tar-free gas through an ammonia - absorbing acid-solution at a temperature above the water - saturation point of the gas but low 100 enough to preclude substantial deposition of ammonia sulfate in said solution; conducting said ammonia-charged solution into a saturation - bath; dehydrating said ammonia-free gas and then passing it through 105 said saturation-bath to effect deposition of the ammonium sulfate; and then passing said gas to the further operations for the recovery of benzol and its homologues; substantially as specified.

4. In a process for the recovery of benzol and its homologues from benzol - charged gas, the combination of steps that consists in: electrically precipitating the tar residue from the gas while the latter is still hot 115 enough to preclude appreciable absorption of benzol by the tar precipitated; and then passing the gas through the further operations requisite to the recovery of the ammonia and the benzol; substantially as specified.

5. In a process for the recovery of tar, ammonia and benzol, and its homologues, from gas charged with them, the combination of steps that consists in: electrically precipitating the tar residue from the gas while the gas is enough superheated substantially to preclude the tar from absorbing the benzol, and its homologues, in the gas; passing the tar-free gas through an ammonia-ab- 125 130

sorbing acid-solution at a temperature above the water-saturation point of the gas but low enough to preclude substantial deposition of ammonium sulfate in said solution; 5 conducting said ammonia-charged solution into a saturation-bath; dehydrating said ammonia - freed gas and then passing it through said saturation-bath to effect deposition of the ammonium sulfate; and then 10 passing said gas to the further operations

for the recovery of benzol and its homologues; substantially as specified.

In testimony whereof, I hereunto set my hand in the presence of two subscribing witnesses.

JOSEPH BECKER.
